UNITED STATES PATENT OFFICE.

WILLIAM E. BAKER, OF ERIE, PENNSYLVANIA, ASSIGNOR TO WEBB ENGINEERING COMPANY, OF ERIE, PENNSYLVANIA, A COMMON-LAW TRUST.

FUEL-GAS-GENERATING PLANT.

Application filed January 25, 1924. Serial No. 688,550.

To all whom it may concern:

Be it known that I, WILLIAM E. BAKER, a citizen of the United States, residing at Erie, in the county of Erie and State of Pennsylvania, have invented certain new and useful Improvements in Fuel-Gas-Generating Plants; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to fuel gas generating plants, and has for its object the provision of suitable mechanism adapted to supply fuel oil and air to a burner apparatus, not shown, in proper proportions without raising the pressure of said oil and air substantially above that of the atmosphere.

The means which I prefer and hereinafter describe consists of a pump-barrel in which a reciprocating plunger operates to draw into said barrel an amount of fuel oil which is measured by the cubic capacity of said barrel at each stroke of the plunger. This pump mechanism is provided with means whereby the length of the stroke of the plunger may be automatically varied, as may be desired. The means for supplying air to the burner apparatus, consists of a fan having a shutter mechanism in its intake adapted to be automatically opened and closed.

Another feature of this invention is the provision of mechanism whereby both the fan and pump can be operated from one source of power. And lastly to provide mechanism whereby said fuel pump and air circulating mechanism can be controlled to vary the quantity of oil and air which the mechanism supplies to the fuel burner, not shown.

These and other features of this invention are hereafter described and pointed out and are illustrated in the accompanying drawings, in which:

Figure 1 is a side view of the motor driven pump and fan mechanism of my invention with the front plate removed and portions thereof broken away showing a central section of a portion thereof on the line 1-1 in Fig. 2.

Figure 2 is a left hand end view of Fig. 1.

Figure 3 is a transverse section on the line 55 3-3 in Fig. 1.

Figure 4 is a section on the line 4-4 looking at the right hand end of Fig. 1.

Figure 5 is an enlarged plan view of a portion of the pump plunger and pitman 60 shown in Fig. 1, removed from the machine.

In these drawings E indicates a motor, preferably electric, of usual construction, on one end of the shaft F' of which is secured a fan F² of usual construction, and on the opposite end of said shaft I secure a worm gear F³. The fan F² is enclosed in a fan case of usual construction, having a central air inlet opening f which is controlled by a swinging shutter f' secured on a rock-shaft, 70 see Fig. 2, provided with a gear pinion f³, so that said shutter can be swung thereby upwardly in a slot f⁴, see Fig. 1, to partially or entirely close the air inlet opening f, as hereinafter described.

F⁴, see Fig. 5, indicates the air outlet from the fan case, with which is connected the burner apparatus, not shown.

Upon the motor and fan housing, is secured a pump frame G, including a pump 80 barrel G' in which a plunger G² operates, said pump barrel being provided with the usual stuffing-box and packing mechanism G³.

This pump barrel G' is provided with 85 transverse inlet and outlet valve chambers g and g' to which inlet and outlet tubes H and D² are coupled in the usual manner.

The inlet valve chamber g is provided with a removable valve seat, g², upon the 90 upper end of which a valve ball g³ rests, and the outlet valve chamber g' is provided with a stationary valve seat, upon which the outlet valve ball g⁴ rests, both valves opening upwardly. When the pump plunger G² 95 recedes, oil will be drawn into the pump barrel through the inlet tube H, and when the plunger advances, the contents of the barrel will be forced outward through the outlet tube D² connected with the vapor generating loop D of the burner apparatus hereinbefore described.

Transversely across the opposite end of the mechanism, see Fig. 4, a shaft J is mounted in suitable bearings j and housing 105 J'. Secured upon said shaft J is a worm

gear wheel J^2 which meshes with the gear worm F^3 , by means of which the shaft J is rotated.

On the opposite end of the shaft J is secured a crank disc K having a wrist pin K' . Journalled on the wrist pin K' is a pitman L , the opposite end of which is bifurcated, see Fig. 8, and is pivoted to a sliding block L' on the plunger rod G^2 of the 10 pump. This plunger rod G^2 is provided with a head G^3 see Fig. 8, with which the sliding block L' engages, for the purpose of receding said plunger, during a portion of the rotation of said crank disc.

15 Stationarily secured upon said plunger rod G^2 is a clamp ring M , see Figs. 1 and 5, by means of a screw or bolt m , and pivoted to said clamp ring is an arm, N , preferably bifurcated, having cut into the lower edge thereof a series of ratchet teeth n , said teeth being adapted to engage a suitable surface on said sliding block L , to cause said plunger rod G^2 to move forward to force the contents of the pump barrel outwardly 20 through the outlet tube D^2 .

25 For the purpose of adjusting the length of the forward thrust of the plunger rod G^2 , I provide a vertically slidable rod P , see Fig. 3, which is slidably mounted in the 30 pump frame G . Said rod P is provided with a key-way into which a pin, on the screw p in the frame G , projects for the purpose of preventing the turning of the rod P .

35 Upon the upper end of the slidable rod P is secured an arm P' which extends over the plunger rod G^2 , and secured in said arm P' is a rod P^2 which is parallel with said plunger rod G^2 .

40 Secured to the ratchet arm N is a roller n' which rests upon the rod P^2 , so that said roller n' can roll back and forth on said rod P^2 during the reciprocation of the plunger G^2 .

45 For the purpose of operating the slidable rod P and fan shutter f , a rock shaft, R , is mounted in suitable bearings, r , on the machine frame. On one end of said rock-shaft, R , is a segment of gear teeth R' which meshes with the teeth of the pinion f^3 , on the shaft f^2 of the fan shutter f , and on the opposite end of said rock-shaft, R there is a cam lever, R^2 , which extends under the lower end of the slidable shaft P .

50 To cause the rock-shaft R to rotate there is a lever R^3 secured thereon, by means of which, when said lever is caused to swing in the direction of the arrow in Figs. 2, 3 and 4, the cam R^2 moves the rod P , upwardly 55 which thereby lifts the ratchet arm N so that the sliding block L' on the plunger rod G^2 will slide thereon until said block engages a tooth which remains in the line of travel of said block, when the plunger rod will be forced to travel in unison with

said block L' , so that the compressing thrust of said plunger rod is thereby shortened. Simultaneously with the lifting of said ratchet arm, N , the gear segment R' causes the fan shutter f' to swing upwardly, and 70 partially or entirely close the air inlet opening f , of the fan housing, so that as the thrust of the pump plunger is shortened, the air intake opening of the fan housing is correspondingly reduced, so that the 75 proper proportions of air and liquid fuel will be, at all times, maintained and supplied to the burner apparatus, whatever the quantity of the mixture. By thus increasing or diminishing the quantity, the 80 heat generated will be increased or diminished.

The lever R^3 is shown as convenient for manual operation, but it is apparent that the same can be operated, by thermally controlled mechanism, as well as by pressure controlled mechanism, so that the action of 85 said mechanism and burner apparatus will be automatic.

While I have shown and hereinbefore described a plunger pump mechanism for furnishing a measured supply of fluid fuel, and a rotary fan for supplying air to the burner apparatus, it will be obvious that it may be possible to use other types of mechanism for these purposes without departing from the scope of my invention, and I therefore do not desire to limit myself to the exact form and type of apparatus and mechanism shown and described. 90

Therefore having fully shown and described my invention, so that others can utilize the same, what I claim as new and desire to secure by Letters Patent is:

1. In a fluid fuel generating plant, a 105 pump barrel, inlet and outlet valve mechanism communicating therewith, a plunger operating in said pump barrel, a head on said plunger, a slidable block on said plunger, crank and shaft mechanism, a pitman pivoted to said block and to said crank, 110 motor and gear mechanism to rotate said shaft and gear mechanism, a swinging arm having a series of ratchet shoulders thereon 115 stationarily secured to said pump plunger adapted to be engaged by said block, and mechanism to vertically adjust said swinging arm.

2. In a fluid fuel generating plant, a 120 pump barrel, inlet and outlet valve mechanism communicating therewith, a pump plunger in said barrel, a head on said plunger, a slidable block on said plunger, 125 shaft and crank mechanism, a pitman pivoted to said block and to said crank, motor and gear mechanism to rotate said shaft and crank mechanism, a swinging arm having a shoulder thereon stationarily secured on said plunger, and adapted to be engaged by said slidable block, a vertically slidable 130

rod, means thereon to engage and support said swinging arm, and rock-shaft and cam mechanism to operate said vertically slideable rod.

5. 3. In a fluid fuel generating plant, a pump, crank shaft, gear, and pitman mechanism to operate said pump, mechanism to regulate the action of said pitman mechanism, a fan, a valve to control the admission

of air to said fan, a rock-shaft, a cam on ¹⁰ said rock-shaft to actuate said pitman regulating mechanism, and gear mechanism on said rock-shaft to operate said fan valve, whereby the action of said pump and fan can be simultaneously controlled. ¹⁵

In testimony whereof I affix my signature.

WILLIAM E. BAKER.
